UNITED STATES PATENT OFFICE.

LAZARD KAHN, OF HAMILTON, OHIO, ASSIGNOR TO THE F. & L. KAHN & BROS., OF SAME PLACE.

DESIGN FOR AN OPEN-FRONT STOVE.

SPECIFICATION forming part of Design No. 20,831, dated June 16, 1891.

Application filed February 14, 1891. Serial No. 381,525. Term of patent 7 years.

To all whom it may concern:

Be it known that I, LAZARD KAHN, of Hamilton, Butler county, Ohio, have invented a certain new and original Design for Open-Front Stoves, of which the following is a specification, reference being had to the accompanying drawing, which shows in perspective an open-front stove embodying my new design.

My design may be described as follows, referring to the drawing.

Two vertical jambs A A bear a flat top B,

projecting to the rear of the jambs, the flat top bearing at its rear the upwardly-projecting back piece C, the fire-basket D and blower 15 F being disposed in the space between the jambs and projecting as a bow therefrom.

I claim—

The design for an open-front stove, as herein described and shown.

LAZARD KAHN.
